UNITED STATES PATENT OFFICE

2,612,144

STEAM BOILER WITH EQUALIZED WATER LEVEL

David M. Schoenfeld, New York, N. Y., assignor to
Combustion Engineering-Superheater, Inc., a
corporation of Delaware

Application September 16, 1947, Serial No. 774,219

3 Claims. (Cl. 122—328)

1

This invention refers to steam-generating boilers and particularly to such boilers that are associated with furnaces in which the distribution of the products of combustion from the furnace through the boiler is substantially uneven.

The majority of bent tube boilers have their fuel burners located so that the flames are directed transversely to the axes of the drums. This of course results in substantially uniform distribution of the products of combustion and consequent substantially uniform steam generation across the width of the boiler. As a result downcomers are usually arranged at the ends of the drums, the arrangement and numbers being symmetrical. However, in many instances, especially aboard ships and naval vessels in particular, it is advisable to arrange the fuel firing equipment so that firing occurs substantially parallel to the axes of the drums. In boilers of the latter type that are operated at extremely high rates, or are "forced," it has been found that a temperature gradient exists in the flue gases flowing over the tube bank. This temperature gradient increases from the front of the boiler, which is the side wherein the burners are located, to the rear or opposite side remote from the burners. Thus a larger temperature differential exists between the flue gases and the water in the tubes at the rear than at the front, naturally resulting in higher rates of steam generation in those tubes adjacent the rear of the boiler.

Furthermore, in boilers operated at high rates, it has been noted that the gases tend to pile up at the rear of the furnace and the pressure of the gases is higher there than toward the front. This results in increased rates of flow of the gases over the tubes in the rear portion of the tube bank and, from the known laws of heat transfer, increased rates of heat transfer from the gases to the boiler tubes, and hence increased rates of steam generation in those tubes.

The net result of these phenomena is a rate of steam generation which increases from the front to the rear of the boiler and an actual water level in the steam drum that is higher in the rear than in the front due to the greater amount of steam-water mixture being delivered there. This is objectionable in that it reduces the effective steam separating space in the steam and water drum and causes an undesirable longitudinal flow of water through the drum.

It is an object of this invention to provide an improved boiler that will overcome the above mentioned objections.

Additional objects of the invention will appear from the following description and drawings in

which are set forth in detail the preferred embodiment of the invention.

Figure 1 is a cross section in elevation, taken on line 1—1 of Fig. 2, through a steam boiler unit embodying one form of the invention.

Figure 2 is a cross section in plan taken on line 2—2 of Fig. 1.

Figure 3 is an end view of the right side of Fig. 1.

10 The boiler unit illustrated comprises an upper steam and water drum 1 and a lower water drum 2 interconnected by a main bank of tubes 3. Associated with the boiler is furnace 4. On the side of the furnace opposite the main bank of tubes 3 is a second bank of tubes 5 connected at its bottom end to a second water drum 6 and at its top end with the steam and water drum 1. Front downcomers 7 and rear downcomers 8 interconnect the steam and water drum 1 with the bottom drums 2 and 6. These downcomers are located adjacent the front and rear ends of the drums as shown; for a purpose later to be made evident there are more downcomers adjacent the rear end than there are adjacent the front end.

25 The represented furnace is enclosed by front and rear walls 9 and 10 and an end wall 11, the front side wall 9 being provided with burner openings 12 through which the burners 12a, such as oil burners, project the fuel and air for combustion into the furnace toward the rear wall 10. The main bank of boiler tubes 3 is bounded by the furnace walls 13, 14 and 15 (best shown in Fig. 2). Side walls 13 and 14 which join the furnace walls 9 and 10 respectively, are in effect a continuation thereof and direct the flow of gases from the furnace through the bank. Wall 15 rearward of the bank with respect to gas flow through the bank, joins said walls 13 and 14 to direct the gases leaving the main bank 3 into off-take 16. The furnace 4 is further provided with a bottom 17.

30 A casing 18 encloses all of the walls of the furnace, the boiler and the bottom 17 of the furnace and is spaced from said walls and bottom to provide a conduit 18a for the flow of air for combustion to slotted openings 12b leading to the burner openings 12. An inlet 19 for the air for combustion is provided adjacent the wall 10 opposite the burner wall 9. Where the drums pass through 35 the casing an air-tight seal is provided so that air under pressure may be conveyed through the casing. The casing may be constructed in sections so as to be removable and provide access to the various parts within the casing such as the downcomers 7 and 8 and the burner openings 12. 40 A superheater 20 may be provided within the

55 Additional objects of the invention will appear from the following description and drawings in

main boiler bank 3 comprising a bundle of U-shaped tubes connected to inlet and outlet headers 21 and 22 (see Fig. 2) which in turn are connected to inlet and outlet connections 23 and 24 passing through the casing 18 by way of seals 25 and 26. The return bends of the superheater extend into a pocket in the side wall 9, and wall 9 is corbelled inwardly on the furnace side of the superheater to deflect the furnace leaving gases away from said pocket.

As mentioned above, in a boiler in which a bank of steam generating tubes receives a predominant portion of heat from products of combustion or hot gases adjacent one end thereof, the tubes adjacent said end will generate steam at higher rates than the remaining tubes of the bank. This condition prevails particularly at high rates of steaming or under "forced" rates, at which a distinct temperature gradient exists in the flue gases flowing over the tube bank; the gas temperature decreasing from the end of the bank receiving the predominant portion of the heat toward the other end. This unequal distribution of heat to the bank of steam generating tubes may be caused by a number of influences, such as flow of the products of combustion longitudinally of the drum or bank, whereby the products impinge against a wall and pile up there to be deflected therefrom into the adjacent end of the tube bank resulting in a greater proportion of the products passing through said end of the bank than through the remaining portion.

As shown in the drawings the burners 12a mounted in openings 12 direct the flame through the front furnace wall 9 into the furnace in direction longitudinal to the steam drum 1 and to the banks of tubes 3 and 5 and toward the rear furnace wall 10. The products of combustion pile up against wall 10 and the pressure of the products is higher there than toward the burner wall 9. This results in relatively increased rates of flow of the products over each tube bank portion adjacent wall 10, and from the known laws of heat transfer, increased rates of heat transfer occur from products to boiler tubes at that location and hence increased rates of steam generation in those tubes. Obviously the same unbalanced heat flow to the main tube bank will occur if the furnace leaving gases are directed as by baffling to enter the bank at one end thereof, or if a conduit delivers hot gases to enter the bank at one end thereof.

The result of the increased steam and water discharge from the steam generating tubes receiving the greater proportion of the heat of the products, is to raise the level of the water in the steam and water drum 1 above these tubes while the water level above the remaining tubes is at a substantially lower level. The resulting water level in the drum may conceivably be shown approximately by the dashed line 27 in Fig. 3. The location within the drum where the greatest proportionate steam release occurs then has the least steam space above the water level for the separation of steam from water. For reasons earlier indicated this is objectionable.

To overcome this objection I provide, according to the invention, the end of the steam drum 1 experiencing the greatest proportional steam generation with a downcomer area to the water drum or drums (2 and 6) therebelow which is greater than the downcomer area at the opposite end of the steam drum. In the drawing hereof the former area is represented by the three rows

of downcomer tubes 8 at the boiler rear while the latter is represented by the single row of downcomers 7 at the boiler front (see Figs. 2 and 3). Such greater downcomer area 8 withdraws a proportionately greater amount of water from the overloaded rear end of the steam drum and thereby lowers the water level adjacent that end, and by proper choice of the two downcomer areas 8 and 7, the water level in the steam drum 1 may be caused to be substantially the same from one drum end to the other.

In this manner a greater average steam releasing space becomes available, which is most desirable. Furthermore, the greater amount of water withdrawn from the most active portion of the steam drum will be delivered to the most active portion of the water drum, thereby assuring ample supply of water to the tube bank where the circulation is most rapid. Also there will be a substantial reduction in the longitudinal flow of water through the steam drum 1 from the overactive to the underactive end. In the lower water drums 2 and 6) a minimum end flow is desirable since the water in it is thus quieter and increases the tendency for solids to settle out. In the upper drum, the improvement here disclosed contributes to the maintenance of a more nearly horizontal water level, since for flow to occur requires a gradient or head.

The larger number of downcomer tubes 8 at the rear of the boiler adjacent wall 10, results in a deeper rear casing. Since in the normal arrangement air for combustion enters at the upper portion of the rear casing, flows down through the rear casing, thence underneath the boiler and upward in the front casing to the fuel burners in wall 9, the friction loss of the air flowing down the rear casing is reduced. Although the depth of the front casing (housing downcomer tubes 7) is reduced in the same increment dimension that the depth of the rear casing is increased, the effect on the friction loss of flow in the front casing is minimized as the required quantity of flow upward in the front casing is diminishing by virtue of the quantities entering the fuel burning devices in opening 12. This beneficial effect is achieved without increase in the weight or overall dimensions (or box volume) of the boiler unit. In fact, if downcomer tubes are arranged in equal numbers front and rear, generally the resulting depth of front casing is greater than required or desirable.

While the preferred embodiment of my invention has been shown and described, it will be understood that changes in construction, combination and arrangement of parts may be made without departing from the spirit and scope of the invention as claimed.

I claim:

1. In a steam boiler unit, an associated furnace having four sides, burners in a first side wall of the furnace projecting the fuel to be burned toward the opposite or second side wall with greatest concentration in released heat adjacent thereto, a steam and water drum arranged with its axis transversely to said first and second furnace walls, spaced water drums below and parallel to said steam drum, two banks of steam generating tubes interconnecting said water drums with the steam drum for discharge of steam and water mixture into the steam drum, one of the banks facing a third side wall, the other bank forming the remaining side of the furnace; walls enclosing said last named bank of tubes and join-

ing said first and second furnace walls for directing the flow of gases from the furnace through said last named bank transversely to the steam drum, and downcomer tubes for a flow of water therethrough of substantially constant density, said tubes interconnecting the ends of the steam drum and the water drums and located outside of the bank-enclosing walls, the total cross-sectional inside area of downcomer tubes adjacent said second furnace wall being greater than the total cross-sectional inside area of the downcomer tubes adjacent said first furnace wall in substantial proportion to the ratio of the heat that is absorbed by the half of each of said banks adjacent said second furnace wall to the heat that is absorbed by the half of each of said banks adjacent said first furnace wall, whereby to provide for faster outflow of water from the steam drum end that connects with the most highly heated portions of said banks of steam generating tubes in order substantially to equalize the water level throughout the length of said steam drum.

2. In a steam boiler unit, an associated furnace, burners in a first wall of the furnace projecting the fuel to be burned toward the opposite or second wall with greatest concentration in released heat adjacent thereto, a steam and water drum arranged with its axis transversely to said first and second furnace walls, a water drum below the steam drum, a bank of steam generating tubes interconnecting the drums and discharging steam and water mixture into the steam drum; boiler walls enclosing said bank of tubes and joining said first and second furnace walls for directing the flow of gases from the furnace through the bank; a further wall on the upstream side of the bank with respect to gas flow and joining said boiler walls and a bottom under the furnace; downcomer tubes for a flow of water therethrough of substantially constant density, said tubes interconnecting the ends of the steam drum and the water drum and located outside of the bank-enclosing walls, all of the downcomer tubes being of the same diameter and the number thereof adjacent said second wall being greater than that adjacent said first wall in substantially the same proportion that exists between the greater heat concentrated adjacent said second wall and the lesser heat concentrated adjacent said first wall, whereby to provide for faster outflow of water from the steam drum end that connects with the most highly heated portion of said steam generating tube bank in order substantially to equalize the water level throughout the length of said steam drum; and a casing enclosing the walls of the furnace, bank and bottom and spaced therefrom to form a conduit for flow of air for combustion from said second wall via

the bottom conduit to said first wall, the spacing from said second wall being greater than the spacing from said first wall; and means in said burners for receiving said air for combustion.

3. In combination with a steam boiler having an upper steam and water drum, a lower mud drum arranged substantially parallel thereto, and a substantially uniform and generally upright bank of tubes extending longitudinally of and connected between said upper drum and said lower drum for generation of steam and for delivering said steam to the upper drum; a furnace arranged in heat exchange relation with said tube bank and having a first and a second side wall, said walls being spaced apart and positioned normal to the longitudinal axes of said drums; said first side wall being arranged adjacent one vertical end of said tube bank and said second side wall being arranged adjacent the other opposite end of said tube bank; burner means positioned in said first side wall only for discharging a stream of fuel into said furnace for combustion therein, said combustion of fuel causing a greater heat release in a region adjacent the second furnace side wall than in a region adjacent the first furnace side wall; first and second conduit means located outside the furnace and connecting the upper drum with the lower drum for feeding water to said lower drum of substantially constant density, said first conduit means being positioned adjacent said first side wall, said second conduit means being positioned adjacent said second side wall and having a cross-sectional flow area which is substantially greater than the cross-sectional flow area of said first conduit means, the cross-sectional flow area of said first and second conduit means being substantially proportional to the ratio of heat absorption of that half of said tube bank that adjoins said first side wall to the other half that adjoins said second side wall, whereby to provide for faster outflow of water from said upper steam and water drum end that connects with the most highly heated portions of said bank of steam generating tubes in order substantially to equalize the water level throughout the length of said steam drum.
